ELECTRODE HOLDER

Frank R. Smith, Los Angeles, Calif.

Application March 10, 1944, Serial No. 525,874

11 Claims.

(Cl. 219—8)

My invention relates to an electrode holder, and an important object of the invention is to provide a streamlined electrode holder that does not have any projecting levers, handles or other projecting elements that will interfere with the holder being pulled through an opening by the cord.

Another object of the invention is to provide an electrode holder that can be quickly assembled or quickly dismantled for replacement and repair.

A still further object of the invention is to provide a holder of the character described that will provide an attractive appearance and will provide housing means that will not turn in the operator's hand, but will afford an efficient gripping shape.

My invention also has for its objects to provide such means that are positive in operation, convenient in use, easily operated, economical of manufacture, relatively simple, and of general superiority and serviceability.

The invention also comprises novel details of construction and novel combinations and arrangements of parts, which will more fully appear in the course of the following description. However, the drawing merely shows and the following description merely describes one embodiment of the present invention, which is given by way of illustration or example only.

In the drawing, like reference characters designate similar parts in the several views.

Fig. 1 is a top plan view of an electrode holder embodying the foregoing objects.

Fig. 2 is a longitudinal section, taken on the line 2—2 of Fig. 3.

Fig. 3 is a longitudinal section at right angles to Fig. 2, and taken along the line 3—3 of Fig. 2.

Fig. 4 is a longitudinal section, partly in elevation, of the forward portion of the tool in a different position than shown in Fig. 3.

Fig. 5 is a transverse section, taken on the line 5—5 of Fig. 3.

Fig. 6 is a perspective view of an element comprised in the device.

Referring more in detail to the drawing, the reference numeral 7 generally designates a housing provided with upstanding flanges 8. The rear end of the housing has a hollow, tapered portion 9 into which leads a cable 10. The wires in the cable 10 are connected in a bore 12 in the rear face of a head member 13 at the end of a base member 14, which is disposed longitudinally of the device inside the housing 7. Screws 15 bolt the base 14 in position in the housing. A set screw 16 firmly holds the wires of the cable 10 in position in the bore 12.

The head 13 is provided with a hook or tenon member 17 for engaging a recess 18 at the rear end of a handle 19. The forward end of the

handle 19 has another recess 20 for receiving an end 21 of a lever 22. The lever 22 has a slot 23 for receiving a stationary pivot pin 24 mounted upon ears 25 on the base 14.

5 The lever 22 also carries a pintle 26 supported between brackets 27 on the lever 22. A flat spring 28 has one end 29 hooked around the pintle 26, while the other end of the spring 28 bears against the base 14.

A portion 30 of the base 14 projects forwardly beyond the housing 7 and carries a gripping jaw 31. A screw 32 fastens the jaw 31 upon the base portion 30. The jaw 31 has a circular, center pocket 33 and grooves 34 radially of the pocket. The lever 22 has a circular boss 35 that is received by the pocket 33 when the lever 22 is in the closed position shown in Fig. 4. The electrode engaging face of the boss 35 is downwardly inclined toward the left in Fig. 4, so that this face may be substantially parallel with the bottom of the pocket 33 when the jaws are open.

An insulating hood 36 receives the projecting portion 30 of the base 14. A screw 37 fastens the hood 36 on said portion 30. A cap 38 encloses the top and sides of, and is substantially coextensive with the outer faces of the lever 22. A screw 39 fastens the cap 38 in place. A small pin 42 on the lever side of the jaw member 31 fits into a corresponding recess in the base 30, 20 to prevent the jaw 31 from turning on the base.

In the operation of my device, the cable 10 is, of course, connected in a suitable electric circuit. By depressing the handle 19, the lever 22 is swung clockwise in Fig. 3, around the pin 24 as an axis, and against the action of the spring 28. This movement opens the jaw lever 22 for the reception of a welding rod 40. The rod 40 may be placed in any of the radial grooves 34 of the lower, relatively stationary jaw 31. Then upon release of the handle 19, the spring 28 causes the lever 22 to move the boss 35 to a clamping position with respect to the rod 40, as shown in Fig. 3. Of course, the rod 40 may be released by depressing the handle 19.

45 In assembling the device, the housing 7 is slid rearward upon the cable 10, and the wires in the cable are fastened in place in the recess 12 by the set screw 16. The lever 22 is slid longitudinally so that its hook member 17 engages the pin 24. This construction avoids the necessity of inserting the pin 24 after the lever is assembled on the base, and provides means whereby the lever and base may be quickly disassembled for repair or replacement. The handle 19 is then slid laterally to a position to which its end grooves 18 and 20 are respectively engaged by the hook 17 and the inner end 21 of the lever 22. Then the housing is slid forward along the base 14 until substantially in the position shown in the drawing. In this position, the flanges 8 prevent lat-

50 55 60

eral displacement of the handle 19. Thereupon the fastening screws 15 secure the housing in place.

It is to be noted that the housing 1, the handle 19, the hood 36 and the cap 38 are of insulating material, e. g., heat-resistant plastic, wood, or the like. Moreover, it will be readily seen that the present device is streamlined and avoids the use of projecting handles or levers. One advantage of my construction is that it may be pulled through a hole in parts being welded, by merely pulling on the cable 10. The streamlined nature of the present holder will permit to slide easily through holes in the structure. The flat sides of the flanges 8 provide an effective grip for the operator.

While I have illustrated and described what I now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. In an electrode holder, a base member and a pivoted lever member, the members having hook and pin pivotal connecting means, the hook carrying member being slidable lengthwise to effect engagement or disengagement of the hook with the pin, the members having welding rod gripping jaws, and means to insure engagement of said pivotal connecting means between said members.

2. In an electrode holder, pivoted base and lever members, the members having hook and pin connecting means, the hook carrying member being slidable lengthwise to effect engagement or disengagement of the hook with or from the pin, the members having welding rod gripping jaws, and a lever control handle engaging the base and hook-carrying member and disposed to insure connection of one member to the other.

3. In an electrode holder, an insulating housing, a conductive base in the housing, a jaw on the base, a lever having a pivoted connection with the base and providing a jaw cooperating with the jaw on the base, spring means tending to move the jaws to a closed position, and an operating handle movably engaging both a relatively fixed portion of the base and a portion of the lever to maintain the pivotal connection between said lever and said base, said handle spanning the space therebetween.

4. In an electrode holder, an insulating housing having an opening in the top thereof, a conductive base in the housing, a jaw on the base, a pivoted lever on the base providing a jaw cooperating with the jaw on the base, spring means tending to move the jaws to a closed position, an operating handle having a lateral sliding connection with the base and with the lever, the handle spanning the space between such connections and disposed substantially within the opening in said housing, the walls of the opening in the housing securing the handle against lateral displacement.

5. In an electrode holder, an insulating housing, a conductive base in the housing, a jaw on

the base, a pivoted lever on the base providing a jaw cooperating with the jaw on the base, spring means tending to move the jaws to a closed position, and an operating handle having a tenon and recess connection with the base and having a tenon and recess connection with the lever, the handle spanning the space between such connections and being thereby movably supported.

6. In an electrode holder, an insulating housing, a conductive base in the housing, a jaw on the base, a pivoted lever on the base providing a jaw cooperating with the jaw on the base, the lever and base having hook and pin connecting means relatively slidable to effect a connection thereof, and an operating handle having a tenon and recess connection with the base and having a tenon and recess connection with the lever, the handle being arranged to prevent disconnecting sliding movements of the hook and pin.

7. In an electrode holder, a hand piece, pivoted base and lever members in said hand piece providing jaws for gripping a welding rod, the lever member having a rearwardly projecting portion, a handle connected with the base member and with the rearward portion of the lever member and spanning the space between such connections, said handle compressible within said hand piece to operate said lever member to open position, and a flat spring tending to move the members to a rod gripping position, the flat spring permitting a compact, streamlined construction.

8. In an electrode holder, a hand piece, pivoted base and lever members providing jaws for gripping a welding rod, the lever member removably fulcrumed on said base member and having a rearwardly projecting portion, a handle pivotally connected with the base member at its rearward end and movably connected with the rearward portion of the lever member and spanning the space between such connections, said handle compressible within said hand piece to move said jaws to open position, and a flat spring bearing against said members to move the members to a rod gripping position.

9. In an electrode holder, a pair of jaws, one of said jaws being fulcrumed on the other at a point intermediate its length, a spring to hold said jaws normally closed, a housing containing said jaws and spring, and means to exert a longitudinal pressure on one of said jaws to maintain its fulcrum connection with the other jaw.

10. An electrode holder including a pair of jaw defining members, one of said members fulcrumed on the other member, a spring to exert a downward pressure on said fulcrumed member normally to hold said members closed and a means to exert a longitudinal pressure on said fulcrumed member to maintain its fulcrum connection with said other member, said means compressible against the action of said spring to operate said fulcrumed member to open position.

11. In an electrode holder, a pair of jaw comprising members dissociably connected for relative movement, spring means to hold said members normally closed, a housing containing said members and spring, a hand operable element associated with said members and exerting longitudinal pressure in one direction on one of said members to maintain pivotal connection between said members, said hand element operable by pressure to within the housing to move said members to open position.

FRANK R. SMITH.
